UNITED STATES PATENT OFFICE.

ARTHUR J. HODGE AND HENRY B. RUGGLES, OF PASADENA, CALIFORNIA, ASSIGNORS
TO AMERICAN PRODUCTS COMPANY, OF ST. LOUIS, MISSOURI.

PULP GATHERING AND TRANSFERRING DEVICE.

1,249,087.

Specification of Letters Patent.

Patented Dec. 4, 1917.

Application filed January 23, 1915. Serial No. 4,035.

To all whom it may concern:

Be it known that we, ARTHUR J. HODGE and HENRY B. RUGGLES, citizens of the United States of America, residing at Pasadena, in the county of Los Angeles and State of California, have invented certain new and useful Improvements in Pulp Gathering and Transferring Devices, of which the following is a specification.

This invention has relation to certain new and useful improvements in pulp gathering and transferring devices and has for its primary object, the provision of new and improved mechanism for gathering pulp from a pulp containing tank and transferring the same to opposite sides of forms or former-sections traveling through said tank.

Another object of the invention resides in the provision of a pulp gathering and transferring device which will be of such construction that the pulp gathering and transferring wheels will be arranged in vertical series and to opposite sides of the moving forms or former-sections, with the wheels of each series positioned on an incline corresponding to the spiral movement of the forms or former-sections.

The invention has for another object, the provision of a device of this character which will be of such construction and operation that it may if desired be readily substituted for the primary compressing and squeezing mechanism of the machine disclosed in our original and co-pending application Serial Number 741 or any other analogous machine, and employed as a primary compressing device to partially compress moving forms or former-sections or employed in connection with any part or parts of any machine or machines of the character disclosed in the referred to application Serial Number 741 or of any other character with which the present device will coöperate.

A further object of the invention resides in the provision of a pulp gathering and transferring device of the above stated character in which each wheel of each and every series will be mounted for rotation upon a separate inclined swinging plate, during upward spiral movement of the forms or former-sections between said series, each plate being resiliently connected with the corresponding plate of the adjacent series to cause the wheels of the various series to gather and transfer to the forms or former-

sections equal amounts of pulp from the tank and also exert equal pressure upon said pulp after transferring the same to the moving forms or former-sections.

The invention has for a still further object, the provision of pulp gathering and transferring mechanism which will be of simple construction and operation and the parts of which will be arranged around the spirally movable connected forms or former-sections in such manner that operation of the mechanism will be governed by the movement of the forms or former-sections, and the pulp gathered by the wheels may be readily transferred to said forms or former-sections and compressed upon the latter, suitable means being carried by the wheel supporting plates to prevent the pulp from adhering to the portions of said wheels opposite the forms or former-sections.

With these and other objects in view, our invention consists in the novel construction, combination and arrangement of parts as will be hereinafter more in detail described and the asserted novelty specifically pointed out in the claims.

In the accompanying drawings which clearly and fully illustrate our invention:

Figure 1 represents a side elevation, with parts in section and parts broken away;

Fig. 2 is a top plan view, with the inclined plate supporting shafts in section;

Fig. 3 is a top plan view of the device in operation, showing the manner in which the pulp is gathered from the tank by the wheels and transferred by the latter to the moving forms or former-sections and compressed around the same;

Fig. 4 is a transverse vertical section through the lower portion of the device, as shown in Fig. 3, the section extending through the lowermost wheels of opposite series; and

Fig. 5 is a detail top plan view of one of the wheel supporting plates and the parts carried by the same.

Referring more particularly to the drawings in which similar reference characters designate corresponding parts throughout the several views, 1 designates the pulp containing tank which receives a continuous supply of pulp from a feed pipe 3 having its discharge end directed toward the open upper end of said pulp containing tank 1.

In this application as in our previously

referred to original application Serial Number 741, and also in our second and co-pending application Serial Number 2051, we employ a stationary shaft 4, extended vertically through an opening 5 in the bottom of said tank 1 and having a spirally extended feed and guide thread 8 formed thereon, preferably below the tank 1, to serve to feed and guide in an upward and 10 spiral direction the forms or former-sections A, through the upwardly flared pulp receiving and directing receptacle 6 and through the tank 1, and around said stationary shaft 4. The receptacle 6 is extended upwardly 15 from the edge of the opening 5 in the bottom of the tank 1 and is spaced from the stationary shaft 4, and it will be understood that this receptacle 6 may be of any suitable or well known construction. It will also be 20 understood that the forms or former-sections A should include outer screens 20 and interior central guide nuts 9 for movement over the spirally extended feed and guide thread 8, as clearly shown in the drawings, 25 and should be adapted to be securely locked together by some suitable and well known means (not shown). The remainder of the forms or former-sections A may be of the construction shown and described in our 30 original and co-pending application Serial Number 741 or of any other construction, as described, and therefore further detailed description of the forms or former-sections A, in this application is believed to be unnecessary. It is also believed to be unnecessary to show or describe in this application, 35 any means for rotating the forms or former-sections A, as they may be operated by the sectional former rotating mechanism disclosed in said application Serial Number 741 or by any other suitable means.

In the present invention we employ pulp gathering and transferring wheels 21, arranged in substantially vertical series and 45 provided with perforated peripheries, around which are secured the screens 22, for gathering pulp from the pulp containing tank 1 and transferring said pulp to the moving forms or former-sections A and partially compressing the same upon said forms or former-sections A.

The wheels 21 are arranged in substantially vertical series, to opposite sides of the forms or former-sections A, and each wheel 55 21 rests upon a supporting plate 23 and rotates upon a stub shaft 24 projecting upwardly from the center of the plate upon which said wheel rests. Each plate 23 has an arcuate shoe or upstanding flange 25, 60 on its upper face and adjacent its inner edge, but inwardly of the perforated periphery of the wheel 21, to prevent liquid from passing through said perforated periphery and the screen 22 around the same, 65 when opposite the forms or former-sections

A, so that the pulp gathered upon the screen 22 of the wheel 21 may at this time be readily transferred to the screens 20 of the forms or former-sections A. The liquid from the pulp may, however, readily pass 70 through the screen 22 and the perforated periphery of the wheel 21 to the interior of said wheel 21, while the pulp is being gathered upon said screen 22 of said wheel 21, and then pass downwardly through the 75 drain opening 26 in the supporting plate 23.

Each supporting plate 23 has a tapered extended end, with which is formed an upwardly directed bearing sleeve 27, the main or body portion of said bearing sleeve 27 80 being connected with the upper face of the supporting plate 23 by means of a bracing and strengthening rib 28. The bearing sleeves 27 of each series are loosely mounted upon an inclined stationary bearing shaft 85 29, which has its lower end secured in the socket 30 at the free or outer end of the bracket arm 31, projecting from the side of the hollow supporting member 32, upon the inclined top 33 of which rests the lowermost 90 supporting plate 23 of the series. The inclined top 33 is provided with a drain opening 34 registering with the drain opening 26 of the supporting plates 23, and the hollow supporting member 32 is provided with 95 an annular outwardly directed flange 35 around its lower edge, which is secured in some suitable and well known manner upon the upper face of the bottom of the pulp containing tank 1, around the drain opening 34 in said bottom. It will be readily seen that the drain opening 34 serves as the outlet for all liquid draining into the hollow supporting member 32 from the interior of all the wheels 21 above the same.

The supporting plates 23 and the wheels 21 are positioned on an angle corresponding to the spiral movement of the forms or former-sections A and each wheel 21 preferably includes a central hub 36 depending 100 from its upper face or web and removably engaged upon the stub shaft 24 provided for the same, so that the wheels 21 may be readily placed in position or removed as desired.

The bracket arms 31 are preferably extended from the low sides of the hollow supporting members 32 and the stationary bearing shafts inclined away from the same. This places the supporting plates 23 with 110 their tapered extended ends positioned downwardly, thereby throwing the weight of the supporting plates 23 and the wheels 21 upon the bearing sleeves 27 and the stationary bearing shafts 29. The strain upon 120 the bearing sleeves 27 and the stationary bearing shafts 29 is somewhat relieved, however, by permitting each supporting plate 23 to rest lightly upon the wheel 21 immediately beneath the same.

By referring to Fig. 2 of the drawings, it will be seen that the stationary bearing shafts 29 as well as the bearing sleeves 27, are arranged at equal distances within the tank 1, and resilient connection between corresponding supporting plates 23 of all of the series is formed by means of the helical spring 37. Each helical spring 37 has one end secured in an ear 38 projecting from the large rounded end of one supporting plate 23, outwardly of the stub shaft 24 of the latter, while the opposite end of said helical spring 37 is mounted upon a bearing post 39 projecting upwardly from the tapered extended end of the corresponding supporting plate 23 of one of the adjacent series, along the adjacent edge of said supporting plate 23 and a short distance from the bearing sleeve 27. It will therefore be evident that all of the pulp gathering and transferring wheels 21 will be at all times resiliently retained in operative position and at equal distances from the moving forms or former-sections A to assure an even and equal deposit of pulp upon all portions of the outer faces or screens 20 of the moving forms or former-sections A and a uniform compression of the pulp by said pulp gathering and transferring wheels 21 to squeeze practically all liquid from said pulp and dry and shape the latter around said forms or former-sections A.

It is believed that the operation of gathering the pulp and transferring the same to the moving forms or former-sections A by means of the pulp gathering and transferring wheels 21, may be readily understood, upon a reading of the foregoing paragraphs, in connection with the drawings of this application, especially Figs. 3 and 4. It is to be remembered, however, that the pulp gathering and transferring wheel 21 and the supporting plates 23 are at all times drawn inwardly toward the upwardly and spirally moving forms or former-sections A, by means of the helical springs 37, and rotation of said pulp gathering and transferring wheels 21 is caused by the upward spiral movement of said forms or former-sections A. It will be apparent that the springs 37 will limit outward movement of the supporting plates 23 and pulp gathering and transferring wheels 21, thereby causing the latter to compress and squeeze upon the screens 20 of said moving forms or former-sections A, the pulp transferred to the latter by said wheels 21. It will also be evident that hot air or any other suitable drying agent may be directed to the interior of the moving forms or former-sections A, by any preferred means (not shown), to assist in drying the pulp while the latter is being compressed around said forms or former-sections A, if desired.

As the complete construction and operation

of this device may be readily understood from the foregoing description taken in connection with the accompanying drawings, it is believed that further detailed description is unnecessary.

70

While the preferred embodiment of the invention has been shown and illustrated, it will be understood that minor changes in the details of construction and arrangement of parts may be made within the scope of the appended claims without departing from the spirit of the invention or sacrificing any of the advantages of the same.

75

What is claimed is:—

1. In a device of the class described, the combination with a movable form; of rotary pulp gathering and transferring members and means for keeping said gathering and transferring members against said form under a yielding pressure.

80

2. In a device of the class described, the combination with a movable form having movement longitudinally of its axis; of series of rotary pulp gathering and transferring members around said form, and actuated by the movement of said form.

85

3. In a device of the class described, the combination with a spirally rotating form; of series of connected pulp gathering and transferring members for gathering pulp and transferring the same to said form and compressing said pulp upon said form.

90

4. In a device of the class described, the combination with a pulp containing tank and a form movable through said tank; of supporting members within said tank and to opposite sides of said form, said supporting members and said tank being provided with liquid drain openings, wheel supporting plates arranged in series above said supporting members, means for supporting said plates, said means being carried by said supporting members and pulp gathering and transferring wheels mounted upon said plates.

100

5. In a device of the class described, the combination with a pulp containing tank and a form movable through said tank; of supporting members within said tank and to opposite sides of said form, said supporting members and said tank being provided with liquid drain openings, wheel supporting plates arranged in series above said supporting members, means for supporting said plates, said means being carried by said supporting members, pulp gathering and transferring wheels mounted upon said plates, said plates having registering liquid drain openings, and means for forming resilient connections between the corresponding plates of said series.

105

6. In a device of the class described, the combination with a pulp containing tank and a form movable through said tank; of supporting members within said tank and

110

115

120

125

130

- to opposite sides of said form, said supporting members and said tank being provided with liquid drain openings, wheel supporting plates arranged in series above said supporting members, means for supporting said plates, said means being carried by said supporting members, pulp gathering and transferring wheels mounted upon said plates, said wheels having perforated peripheries, and screens encircling said peripheries.
10. In a device of the class described, the combination with a pulp containing tank and a form movable spirally through said tank, inclined supporting plates arranged in series around said form and within said tank, a bearing shaft for each series of said plates, the plates of said series being resiliently connected, pulp gathering and transferring wheels mounted upon said plates and provided with perforated peripheries, screens mounted upon the peripheries of said wheels, and upstanding shoes carried by said plates inwardly of the peripheries of said wheels and adjacent the inner edges of said plates.
15. In a device of the class described, the combination with a pulp containing tank, a shaft extended vertically through said tank, and a sectional form movable spirally and upwardly upon said shaft and through said tank; of inclined wheels to opposite sides of said form and arranged in vertical series to gather pulp from said tank and transfer the same to said form and compress said pulp around said form upon upward spiral movement of the latter, and means for supporting said wheels.
20. In a device of the class described, the combination with a pulp containing tank, a shaft extended centrally through the same and a plurality of connected forms mounted for upward spiral movement upon said shaft and through said tank; of a plurality of inclined stationary bearing shafts within said tank, said stationary bearing shafts being spaced equally apart around the first mentioned shaft and the connected forms, a series of inclined supporting plates loosely mounted upon each bearing shaft, the corresponding supporting plates of the series being resiliently connected, a stub shaft mounted upon each supporting plate and a pulp gathering and transferring wheel mounted upon each stub shaft to gather pulp from the tank and transfer the same to the connected forms during movement of the same between the wheels.
25. In a device of the class described, the combination with a pulp containing tank, a pulp gathering and directing receptacle mounted in the bottom of said tank, a stationary shaft extended centrally through said receptacle and through said tank, and connected forms movable upwardly and spirally around said shaft and through said receptacle and tank; of pulp gathering directing and compressing wheels within said tank and arranged in vertical series around said shaft, means for supporting said series of wheels, said wheels being positioned upon an incline corresponding to the spiral movement of the connected forms and engaged with the pulp directed to the outer face of said connected forms by said receptacle, whereby said wheels are caused to rotate around said connected forms to gather and transfer pulp to the latter and compress said pulp around said forms, and means for resiliently retaining said wheels in normal position.
30. In a device of the class described, the combination with a form having an endwise movement between material gathering and transferring wheels; of material gathering and transferring wheels actuated by the movement of said form.
35. In a device of the class described, the combination with a form; of inclined material gathering and transferring wheels arranged around the same and actuated by the movement of said form between them.
40. In a device of the class described; the combination with a form; of concentrically arranged material gathering and transferring wheels arranged in series and coöperating with said form as it moves between them along its own axis.
45. The combination with a form; of rotary material gathering and transferring wheels around said form and coöperating with the same and having an angular engagement with said form, whereby the materials are laid thereon in a spiral direction.
50. The combination with a central form; of inclined rotary material gathering and transferring members adjacent said form and coöperating with the latter.
55. In testimony whereof we affix our signatures in presence of two witnesses.
